Primary Examiner — Cynthia R Underwood

(57) **CLAIM**

The ornamental design for a table computer keyboard, as shown and described.

DESCRIPTION

FIG. 1 is a front view of the table computer keyboard according to my design;

FIG. 2 is a back view of the table computer keyboard of FIG. 1;

FIG. 3 is a left view of the table computer keyboard of FIG. 1;

FIG. 4 is a right view of the table computer keyboard of FIG. 1;

FIG. 5 is a top view of the table computer keyboard of FIG. 1;

FIG. 6 is a bottom view of the table computer keyboard of FIG. 1;

FIG. 7 is a front view thereof, showing the table computer keyboard in an extended state;

FIG. 8 is a back view thereof, showing the table computer keyboard in an extended state;

FIG. 9 is a left view thereof, showing the table computer keyboard in an extended state;

FIG. 10 is a right view thereof, showing the table computer keyboard in an extended state;

FIG. 11 is a top view thereof, showing the table computer keyboard in an extended state;

FIG. 12 is a bottom thereof, showing the table computer keyboard in an extended state;

FIG. 13 is a front view thereof, showing the table computer keyboard in another extended state;

FIG. 14 is a back view thereof, showing the table computer keyboard in another extended state;

FIG. 15 is a left view thereof, showing the table computer keyboard in another extended state;

FIG. 16 is a right view thereof, showing the table computer keyboard in another extended state;

FIG. 17 is a top view thereof, showing the table computer keyboard in another extended state;

FIG. 18 is a bottom view thereof, showing the table computer keyboard in another extended state; and,

FIG. 19 is a perspective view thereof, showing the table computer keyboard in another extended state.

The broken lines shown in the Figures depict portions of the table computer keyboard that form no part of the claimed design.
